UNITED STATES PATENT OFFICE.

EDGAR B. TRAFTON, OF SHERMAN, MAINE.

WINDOW-LOCK.

1,262,410.

Specification of Letters Patent.

Patented Apr. 9, 1918.

Application filed June 25, 1917. Serial No. 176,794.

To all whom it may concern:

Be it known that I, EDGAR B. TRAFTON, a citizen of the United States, residing at Sherman, in the county of Aroostook and 5 State of Maine, have invented certain useful Improvements in Window-Locks, of which the following is a specification, reference being had therein to the accompanying drawing.

10 This invention has reference generally to improvements in that class of inventions known as builders' hardware, and more particularly relates to a window lock.

15 As the primary aim and object the present invention contemplates the provision of novel coöperative means carried by a window casing and by a window sash whereby the sash may be held in various positions of vertical adjustment or if desired the sash 20 may be removably locked in a closed position.

25 It is an additional and equally important object of this invention to provide manually operable cam levers on the lock body, consequently controlling the actuation of the lock.

30 It is a more specific object of the present invention to provide improved resilient pawls integral with the body for coöperation with the opposed teeth on the strip; and to provide improved means for mounting the manually operable levers.

35 Among the other aims and objects of the present invention may be recited the provision of a device of the character mentioned with a view to compactness, and in which the number of parts are few, the construction simple, the cost of production low and the efficiency high.

40 Other improvements and novel details in the construction and arrangement of the various parts of the apparatus will be brought out more in detail in the description to follow, which for a clear understanding of the 45 invention, should be considered in connection with the accompanying drawings, forming a part hereof, wherein is disclosed for the purpose of illustration a convenient and satisfactory embodiment of the invention.

50 It is to be noted in this connection that various minor changes in the construction and arrangement of parts may be made without departing from the spirit of the invention or the principle of operation of the 55 various parts.

The invention is clearly illustrated in the accompanying drawings, in which:—

Figure 1 is a front elevation of the invention applied to a window sash;

Fig. 2 is an enlarged fragmentary front 60 elevation of the device in position, the lock body being shown in sections and in a locked position;

Fig. 3 is a similar view, the lock body being shown in an open position to permit of 65 the actuation of the sash;

Fig. 4 is a transverse section taken on line 4—4 of Fig. 2.

Similar reference characters are employed in all of the above described views, to indicate corresponding parts.

Referring now, more particularly, to the accompanying drawings, there is provided a window casing 1 in which is slidably mounted a sash 2. The strip 3 is mounted 75 on the inner edge of the window casing 1 and arranged adjacent the inner side of the lower sash 2 and assists in guiding the vertical sliding movement of the lower sash. The outer face of the strip 3 is provided 80 adjacent its lower edge with a projection 4 while extending from the outer face above the projection are a plurality of teeth 5. The teeth 5 extend upwardly while other teeth 6 are formed on the outer edge of the 85 strip beneath the projection and are positioned so as to extend opposite from the teeth 5.

Coöperating with the toothed strip is an improved lock for holding the lower sash 90 in a closed position or in various positions of vertical adjustment. In the present instance the lock consists of a body 7 which is rigidly secured to the outer face of the lower sash 2 by means of suitable fastening devices 95 8, and when the sash is in a lowered or closed position the body is preferably arranged approximately opposite the projection 4. The inner edge of the body 7 is arranged in close relation with the outer 100 edges of the teeth as indicated by the numeral 9 while pawls 10 and 11 are formed respectively on the upper and lower ends. The engaging faces of the pawls are curved rearwardly as indicated by the numeral 12 105 while the rear faces thereof are curved toward the straight edges as indicated by the numeral 13 leaving relatively thin resilient portions 14. It is to be appreciated that owing to the inherent resiliency of the metal 110

2
of which the body is formed and because of the construction of the pawls they are normally held in yielding engagement with certain of the teeth but may be readily pressed 5 away from engagement with the teeth when it is so desired. As indicated in Figs. 2 and 3 the pawl is adapted to coöperate with the teeth 5, in holding the window sash in various positions of vertical adjustment while 10 the pawl 11 is adapted to coöperate with the teeth 6 in removably holding the lower sash in a closed position.

With a view toward providing suitable means whereby the lock may be actuated so 15 as to raise the window sash 2 the pawl 11 is provided with a vertical slot 15 while pivotally mounted adjacent the upper end of the slot by means of a transversely extending pin 16 is a manually operable cam lever 20 17. A handle 18 is formed on the outer end of the lever and when this abuts the lower end of the slots as indicated in Fig. 2 it of course will be appreciated that upward movement of the sash is prevented but when 25 the handle is swung upwardly the outer end of the cam lever 17 will engage the inclined edge 19 of the adjacent tooth 6 so as to remove the pawl 11 from engagement with the tooth 6 with which it is in engagement to 30 consequently permit of the raising of the sash.

In order to provide suitable means for releasing the upper pawl 12 from engagement with the tooth 5 so that the sash may be consequently lowered, the pawl 10 is provided 35 with a vertical slot 20 in which is pivoted adjacent the upper end by means of a transverse pin 21 a manually operable cam lever 22 on the outer end of which is formed a handle 23. When the handle 23 is in the raised position as indicated in Fig. 2 the enlarged end thereof lies within the outer edge 40 of the pawl 10 but when this lever is moved downwardly until the shoulder 23' strikes the lower end of the slot the engaging end 45 of the lever will be moved outwardly so as to consequently coöperate with the adjacent tooth 5 and press the pawl 10 from engagement with the teeth to consequently permit 50 of the lowering of the sash.

In view of the foregoing description it is thought that a further detailed description of the operation of the invention is entirely unnecessary. Likewise it is believed that the 55 advantages of the invention will be readily apparent.

As many changes could be made in the above construction and many apparently widely different embodiments of this invention could be made without departing from 60

the scope thereof, and it is intended that all matter contained in the above description or shown in the accompanying drawings shall be interpreted as illustrative and not in a limited sense. It is also to be understood 65 that the language used in the following claims is intended to cover all the generic and specific features of the invention herein described and all statements of the scope of the invention, which as a matter of language 70 might be said to fall therebetween.

Having thus fully described this invention, what is claimed as new and desired to be secured by Letters-Patent, is:—

1. A device of the character described including a strip adapted to be secured in the casing, teeth formed on the outer face of the strip, the teeth adjacent the upper end of the strip extend upwardly while those adjacent the lower end extend downwardly, a 80 lock body adapted to be secured to a window sash, resilient pawls formed on the upper and lower ends of the body for coöperating with the oppositely disposed teeth and adapted for holding the sash in various positions of vertical adjustment or adapted for holding the sash in a closed position, and manually operable cam levers pivoted to the pawls for moving the pawls out of engagement with the teeth to permit of adjustment 90 of the sash.

2. A window lock including a strip adapted to be secured to a window casing, a plurality of upwardly extending teeth formed on the outer face of the strip adjacent the upper end, a plurality of downwardly extending teeth formed on the outer face of the strip adjacent the lower end, a lock body adapted to be secured to a window sash, resilient pawls formed respectively on the upper and lower ends of the body for coöperating respectively with the upper and lower teeth and adapted for either holding the sash in various positions of vertical adjustment or in a closed position, the pawls being provided with slots, a cam lever pivotally mounted in the slot in the lower pawl for moving the lower pawl out of engagement with the downwardly inclined teeth to consequently permit of raising of the sash, 100 another cam lever pivotally mounted in the slot in the upper pawl and coöperating with the upwardly inclined teeth for moving the upper pawl out of engagement therewith to consequently permit lowering of the sash, 105 and a shoulder formed on the upper cam lever for limiting the upward movement thereof.

In testimony whereof I affix my signature.
EDGAR B. TRAFTON.
